UNITED STATES PATENT OFFICE.

CLYDE V. NACHAND AND EDWIN M. RAHM, OF JEFFERSONVILLE, INDIANA.

DEMOUNTABLE RIM.

1,384,774.

Specification of Letters Patent. Patented July 19, 1921.

Application filed October 14, 1920. Serial No. 416,873.

To all whom it may concern:

Be it known that we, CLYDE V. NACHAND and EDWIN M. RAHM, citizens of the United States, and residents of Jeffersonville, in the county of Clark and State of Indiana, have invented new and useful Improvements in a Demountable Rim, of which the following is a specification.

The object of our invention is to provide 10 a demountable rim of relatively simple construction which can be readily attached and detached; and to provide the novel combination and arrangement of parts hereafter described and illustrated in the accompanying 15 drawings, in which:

Figure 1 is a side elevation of the invention applied to an automobile wheel with parts broken away and in section;

Fig. 2 is a transverse section, partly in 20 elevation;

Fig. 3 is a detail perspective view, with member 11 shown in dotted lines;

Fig. 4 is a longitudinal section through 25 the portion of the rim in which member 11 is mounted;

Fig. 5 is an elevational view of the portion of the rim where the sections are divided, one of the sections being shown in a dotted line position to indicate the method 30 of removing and applying that section.

Fig. 6 is a perspective view of member 8; and

Fig. 7 is a perspective view of member 11.

Like numerals indicate like parts in each 35 of the several views.

Referring to the accompanying drawings, we provide a rim 1 having spaced arcuate locking recesses 2 so shaped as to encompass and grip locking lugs 17 in the felly 18.

40 We preferably divide the felly band into twenty equal parts at 19 of which are provided the locking lugs 17, while at the twentieth is provided the transverse angularly disposed slot 3 which is adapted to receive 45 the cam 11 having the angularly disposed slot 12 adapted to receive the lug 14 which is welded on the felly band 21, preferably in the center thereof. We provide a suitable valve opening 4 in rim 1, and a suitably 50 elongated valve opening 19 in felly 18, whereby to permit of longitudinal movement of the rim 1 and valve 22 relative to the felly 18. Rim 1 is made in sections which are connected by a suitable hinge 5, 55 and releasably engaged at the opposite contacting edges of said sections, as shown in

Fig. 1, by the V-shaped projections 6 which releasably engage in corresponding V-shaped recesses 6, one on either side of the rim, as shown in Fig. 5. One of the sections is moved out of engagement with the other in the manner shown in dotted lines in Fig. 5 when the device is to be demounted. We provide a suitable cam screw socket 8, adapted to receive the cam screw 9 which is inserted through opening 13 in extension 10 of cam member 11. We further provide a suitable nut 15 and washer 16 to engage the threaded end of cam screw socket 8, as illustrated in Fig. 2. We provide in rim 1, as shown in Fig. 5, an additional V-shaped recess 20 through which the projections 6 on that side of the rim may be passed in demounting the rim.

75 In use the cam 11 with its angularly disposed slot 12 which engages the lug 14 on the felly band 21 causes longitudinal movement of the rim 1 by reason of a wedging action and securely locks the rim in assembled position. The cam 11 and cam 80 screw 9 are not removed from the wheel to mount or remove the rim. The locking ring in its outer edge is crimped inward or toward the center of the wheel a sufficient amount to hold the rim in a fixed position 85 when the rim is locked in place. On one end of the section of the rim 1, as indicated in Fig. 1, is formed the sectional hinge 5 integral with the rim. The sections of rim interlock and are held in place by a 90 suitable fast pin, the entire hinge being designated as 5 in the drawing. The opposite joints of the sections of rim 1 are held in perfect alinement while under the pressure of an inflated tire. Upon deflation the lock 95 formed by the engagement of projection 6 in recesses 7 loses its property of locking and alinement, thereby allowing the rim to be easily unlocked and removed from the tire in the manner indicated in Fig. 5 of the 100 drawings. The edges of the transverse slot 3 in which cam member 11 seats are disposed at an angle from the axis of the rim to correspond with the disposition of the cam member 11 required.

105 What we claim is:

1. In a device of the class described, the combination of a rim having spaced arcuate locking recesses extending part way into the inner surface of the rim from one side 110 thereof, a felly having similarly spaced locking lugs positioned to releasably engage

- in the aforesaid locking recesses, the felly having a longitudinal slot to permit of shifting the rim and tire valve longitudinally relative to the felly, the rim having diagonally slotted portion, and a wedge plate member slidable into the said diagonally slotted portion in the rim, whereby to permit of readily securing the rim in place and readily detaching same.
2. In a demountable rim of the class described, the combination of a rim having spaced arcuate locking recesses, a felly hav-

ing similarly spaced locking lugs engageable in the aforesaid recesses, the rim having an angularly depressed groove, a slotted 15 cam or wedge member engaging in said groove, a felly band having a projection engaging in the slotted portion of the cam member, and means integral with the aforesaid cam member for moving it and fastening it on the side of the rim.

CLYDE V. NACHAND.
EDWIN M. RAHM.
